J. F. MAKOWSKI

PLASTER LATH

Filed May 29, 1923

INVENTOR.

John F. Makowski

BY *Berry J. Webster*
ATTORNEY

UNITED STATES PATENT OFFICE.

JOHN F. MAKOWSKI, OF STOCKTON, CALIFORNIA, ASSIGNOR TO CALIFORNIA CEDAR PRODUCTS COMPANY, OF STOCKTON, CALIFORNIA.

PLASTER LATH.

Application filed May 29, 1923. Serial No. 642,196.

To all whom it may concern:

Be it known that I, JOHN F. MAKOWSKI, a citizen of the United States, residing at Stockton, county of San Joaquin, State of California, have invented certain new and useful Improvements in Plaster Lath; and I do declare the following to be a full, clear, and exact description of the same, reference being had to the accompanying drawings, 10 and to the characters of reference marked thereon, which form a part of this application.

This invention relates to the building art and particularly to wall construction for 15 both interior and exterior work.

The object of the invention is to produce a composition plaster lath as a substitute for and improvement over the common wooden lath and other familiar types. Reduction of cost, ease in manufacturing, handling and greater efficiency in function are the principal desideratum in the development of the invention.

These objects I accomplish by means of 25 the compositions used and the mechanical combination of the elements as fully set forth hereafter.

The figure of the drawing is a cross section of my improved lath.

Referring now more particularly to the 30 characters of reference on the drawings, the numeral 1 designates the base support for the lath which may be wood, plaster board, heavy card or straw board or any equivalent found suitable.

I apply to the base support a layer or 35 coating 2 of material suitable as a binder and adhesive as, for example, silicate of soda. While this is still soft I sprinkle or 40 otherwise distribute small gravel 3 over the coating of binding and adhesive material.

When the binder and adhesive dries and sets, the gravel is firmly imbedded therein

and the elements are firmly held together as 45 a unit.

It is essential, for various reasons, that the lath be water and moisture proof. In view of the fact however, that it may be desirable to use very inexpensive material for the binder and adhesive, it will probably 50 be found that the cheaper materials are more or less soluble and not impervious to moisture. The utility of the lath would therefore be greatly lessened unless this condition was overcome and, hence, when soluble material is used for such binder, I spray over the exposed surface of gravel a coat 55 of water proofing material 4 such as asphaltum or the like, applied in such a manner as not to fill up the interstices between 60 the gravel and binder, as clearly shown on the drawing.

The lath may be made up in sheets, strips or other desired shapes. When placed on the wall the interstices between and back of the particles of gravel form a most efficient mechanical key for plaster, cement or other plastics used in plastering and cement and stucco work, the wall, when completed, becomes a composite sheet of the great 70 strength and with very little likelihood of its checking, cracking or falling.

Having thus described my invention what I claim as new and useful and desire to secure by Letters Patent is:

A plaster lath comprising a body, gravel sprinkled thereon, means for adhering the gravel to the body, interstices being formed between the particles of gravel and the adhesive means, and a coating of waterproofing material over the exposed surfaces of the gravel particles and the adhesive means but not filling up the interstices therebetween.

In testimony whereof I affix my signature.
JOHN F. MAKOWSKI.
